JOHN P. WEIS, OF NYACK, NEW YORK, ASSIGNOR TO METROPOLITAN SEWING MACHINE CORPORATION, A CORPORATION OF DELAWARE.

THREAD-CONTROLLING MEANS FOR SEWING-MACHINES.

1,328,023.

Specification of Letters Patent. Patented Jan. 13, 1920.

Application filed September 25, 1918. Serial No. 255,665.

To all whom it may concern:

Be it known that I, JOHN P. WEIS, a citizen of the United States, residing at Nyack, in the county of Rockland and State of New York, have invented certain new and useful Improvements in Thread-Controlling Means for Sewing-Machines, of which the following is a specification.

This invention relates to thread controlling mechanism for sewing machines, and while the invention is shown and described for handling looper or under threads, the invention is not limited thereto as by a mere re-arrangement of the various parts it may 10 be used with equal facility for handling needle threads, the object of the invention is the provision of tubular guiding members for conducting the threads to suitable tensions and to the thread nipper device and 15 also to and from the take-up means which take up the slack of the looper threads at certain periods during the stitch-forming cycle of the sewing machine and certain of 20 which tubular guides are adjustable in the 25 direction of their length and with respect to the loopers so as to vary the take-up action on the threads as they are conducted therefrom to the stitching mechanism.

Among the objects of the invention is the 30 provision of an improved thread controlling or handling means for conducting one or more looper threads in a positive manner so as to keep them separate and free from entanglement; which will protect the 35 threads so as to keep them away from the rotary parts of the machine to prevent the winding up thereof; which is so located that it may be always under observation by the operator while the machine is in operation; 40 and which can also be quickly threaded by the operator in a simple manner without disturbing any of the machine parts by reason of the free accessibility of the mechanism.

The invention is particularly useful in 45 sewing machines for making the two-thread chain stitch. It has been difficult heretofore to control the looper threads in sewing machines used for making one or more rows of two-thread chain stitches at high speed and 50 keep the threads separated. It is well understood by those skilled in the art that unless they are separated uniform stitching cannot be produced, while the breakage of the threads and the winding up thereof on

the rotary parts of the machine is a great 55 source of annoyance.

Various forms of thread take-ups comprising reciprocating, as well as rotary devices have been used for the purpose, but the reciprocating take-ups have the disadvantage of not handling the thread precisely because such parts are actuated by an eccentric or crank, and there are two periods of rest during the movement while the eccentrics or cranks are passing the center of 60 rotation at each end of the stroke, while the rotary take-up has the disadvantage of winding up caused by centrifugal force and the rotary action of the moving parts to chafe and break the threads and cause such 65 winding up. Then again as such rotary devices are usually located on the main shaft of the machine this makes it difficult for the operators to get at them for threading as well as adjusting. All these objections are 70 overcome by the present improvement because the threads cannot wind up, all the parts to be threaded are located on the outside of the machine where they are readily 75 accessible, simple to thread and adjust and while the action of the take-up member is 80 rotary, the part thereof acting upon the threads is remote from its rotary driving means.

In the drawings accompanying and forming a part of this specification, Figure 1 is a front view of a Metropolitan long arm top and bottom rotary shaft machine with my improvement applied thereto; Fig. 2 is a detail perspective view of the thread take-up 85 parts, showing the position of the take-up finger with respect to the other parts while the looper threads are being drawn from the supply by the feeding of the work; Fig. 3 is a view similar to Fig. 2, showing the take-up finger in contact with the looper threads to take up the slack as the loopers begin to move backward; Fig. 4 is a view similar to Figs. 2 and 3 with the take-up finger in the 90 position it assumes when the looper threads are taken up to the fullest extent at the time the needles are coöperating with the loopers to enter the looper thread loops; Fig. 5 is a view similar to Figs. 2, 3 and 4 showing the take-up finger as the looper 95 threads are cast therefrom at the completion of the stitch formation; and Fig. 6 is a perspective view of the take-up and nipper 100 105

mechanisms showing the operating connections and the bottom crank shaft of the sewing machine. This view also illustrates the connections from the bottom crank shaft for 5 operating the top rotary shaft, and portions of the oil pan to which certain parts of the take-up and nipper mechanisms are attached.

Similar characters of reference indicate 10 corresponding parts in the different figures of the drawings.

The base of the machine carrying the vertical arm is shown broken away just above the cloth plate line and the three 15 connecting rods are likewise shown broken away it not being deemed necessary herein to show the upper portion of the machine carrying the usual rotary top shaft and crank shaft connections for the said three 20 rods for operating the usual needle bar, since a sewing machine of this kind is described in certain patents heretofore issued to J. P. Weis, among them Patents Nos. 1,118,709 and 1,118,710 dated November 24, 25 1914, so that reference may be made thereto for a detailed description of the three crank rod connections.

The machine is provided with a cloth plate 3, carrying a throat plate 4. The cloth 30 plate is secured to an extension of the arm 2 as at 5, and at the front end to a bracket 6 as at 7, and to a front bearing 8. The bottom of the bracket 6 is secured to the machine base as at 9, the base carries a bottom 35 rotary shaft 10 which operates in the forward bearing 11, intermediate bearing 12 and rear bearing 13. This shaft carries the usual belt wheel 14. The looper mechanism of the machine is generally indicated by 15, 40 the driving mechanism therefor being indicated by 16. The machine base is provided with a rectangular opening 17, to receive an oil pan 18. This oil pan is in the form of a slide having an oil pocket 19 and a front 45 wall 20 and is arranged to slide into the rectangular opening and be secured therein by a screw 21. The cranks of the crank disks 22 of the bottom shaft 10 operate directly over the oil pocket 19 so that the oil 50 dripping from the connection 23 will fall into the pan. Adjacent to the rear bearing 13 is a triangular cam 24 carried by the shaft 10 and this cam operates in a fork 25 of the nipper actuating lever 26. This lever 55 is secured to a rock shaft 27 as at 28 and this shaft 27 rocks in a suitable bearing carried at the upper part of the rectangular opening 17. A lever 30 is secured to the other end of the shaft 27 and has secured to 60 a part thereof the nipper spring 33 which terminates in a forked end, each member of this forked end having an independent yielding action. Each of these forked ends operates with a thread, so that one thread 65 passes over one yielding end and under the

other while the other thread of the pair passes over the first yielding end and under the other whereby the threads are maintained separated, see Fig. 6. The nippers co-act with a nipper plate 34 provided with 70 open slots 35 to receive the looper threads 36. This plate is attached to the front wall 20 of the pan by a screw 37 passing through the shank 38 of the nipper plate, so that it will have a vertical adjustment to and from 75 the nipper spring. The looper threads 36 are conducted by tubes 39 attached to the rear of the machine so as to deliver the threads to the tension 40, which in this instance carries tension disks for the respective threads. Also attached to the wall 20 of the oil pan is a bracket 41 provided with slots 42 to permit vertical adjustment. This bracket is provided with a thread guiding post 43, having an overhanging end 44 located adjacent the nipper plate 34 so as to properly guide the threads. The bracket 41 is also provided with two guide wires 45, extending vertically from the bracket and bent outwardly to facilitate the threading. 80 The bracket 41 also carries cast-off wires 46 located just in the rear of the wires 45, which extend vertically and backwardly so as to co-act with the take-up finger 47. This take-up finger has a thread engaging notch 48 forming a hooked end 49 so as to manipulate the threads 36 in the manner as shown and described. The bracket 41 also carries a post 50 provided with a right-angle portion 51 having thread eyes 52 to guide the threads separately from the take-up finger 47 to thread tubes 53. These thread tubes 53 are adjustably supported in brackets 54 and are secured in position by screws 55. The delivery ends 56 and 57 of the tubes 53 are so located with respect to the loopers 58 and 59 that the staggered portions thereof correspond approximately with the staggered relation of the loopers and the adjustment of the tubes 53 in the direction of their length to and from the take-up, 90 effects the taking up of the threads in the following manner: If the tubes are adjusted toward the loopers a greater thread take-up will result because the looper in its backward movement will tend to draw the threads over the ends of the tubes 56 and 57 at a greater angle whereas if the tubes are 95 adjusted in the opposite direction the threads will not be drawn over the ends of the tubes at so great an angle. Each of the tubes 53 is slotted throughout its length as at 60 except for the portions at each end indicated by 61, and these slots terminate in eyes 62, which facilitates the threading. This same 100 slot arrangement may be provided in tubes 39 if desired, but it is not deemed necessary to show this herein.

The take-up finger 47 is carried by an extension 63 of the connection 23 and is ad- 105

justable in a socket 64 being clamped therein by a screw 65. The finger is bent at right angles as at 66 and is flattened slightly along its sides as at 67 throughout the remainder 5 of its length. This thread finger being carried by the connection 23 which has a rotary motion by reason of its crank 22, the thread engaging end 49 likewise has a rotary motion. As the shaft 10 rotates in the direction of the arrow, Fig. 6, the take-up finger 47 moves forward and downward to the position shown in Fig. 2, then upward to the position shown in Fig. 3 and backward to the position shown in Fig. 4, the movement 15 of the finger from the position shown in Fig. 3 to the position shown in Fig. 4 representing the take-up movement. That is, during this period of movement it is carrying the looper threads while the loopers are moving 20 backward so as to properly control the threads while the needles descend to enter the looper thread loops in the formation of the stitch. Immediately as the needles have entered said loops the threads contact with 25 the cast off wires 46 which disengage the threads from notch 48 and thus permit the slack of the thread loops 68 to be taken up by the loopers, on their forward movement. It will be observed that one of the threads 30 36 passes under and over the spring nipper fork 33 while the other thread alternates crossing over and under so that each of said threads will have one of the members acting thereon to properly clamp the thread while 35 the take-up finger is taking up the slack from the loopers. The disposition of the various guides and cast off wires carried by the bracket 41 is such as to form a path of travel for the threads and confine their lateral 40 movements so that they will be positively under the control of the take-up finger, and that the vertical adjustment of the bracket 41 with respect to the vertical adjustment of the take-up finger in the socket 64 results 45 in changing the time when the finger 47 will contact with the threads to commence the take-up action and also change the time when the threads are cast therefrom as shown in Fig. 5. For instance if the bracket 50 41 is adjusted to a low position so that the finger 47 will just enter below the threads, the time or duration of its contact with the threads will be longer than if the reverse adjustment is made. This is due to the fact 55 that the take-up finger 47 travels in a circle and the vertical adjustment of the bracket 41 intersects the outer portion of the circle in which the take-up finger 47 operates. Therefore if the bracket is adjusted so that 60 the finger 47 just enters below the threads instantly as it moves upward it contacts with and carries the threads in its circular movement upward and over the cast-off wires 46. Now, since the normal position of the 65 threads is controlled by the overhanging

hook 44 and the hook 51 provided with eyes these parts determine the normal run of the threads with respect to the take-up finger 47 and as the cast-off wires 46 are also carried by the bracket in fixed relation to 70 the overhanging guides 44 and 51, they are lowered to a corresponding degree with the bracket 41. Consequently the take-up finger travels higher in relation to the bracket and its members so that the threads are retained by the take-up finger during a greater portion of its movement than they would be if the reverse adjustment were made, viz: raising the bracket 41 so that the take-up finger 47 would enter some distance below 75 the threads. For instance, in Fig. 2 the take-up finger 47 is shown way below the threads and must travel quite a distance before it engages the threads whereas if the bracket 41 were lowered to bring the 80 threads carried by the hooks 44 and 51 down to where the take-up finger is shown in Fig. 2 obviously the duration of contact of the finger with the threads will be longer. The finger 47 coöperating with the cast off wires 85 46 insures an instant release of the threads as the threads contact with such cast off wires see Fig. 5, and even though the machine be turned backward the finger 47 will merely operate in the reverse direction drawing the threads downward slightly but in no case will they wind up or even be broken 90 from the loopers.

From the foregoing it will be observed that the take-up finger in the present instance is a rotary take-up finger, since it is directly connected with one of the driving connections shown herein in the form of a crank of the bottom or main rotary driving shaft and that in operation the thread is 100 moved upward and backward only by the take-up finger and not back and forth as has been the case heretofore.

It will also be observed that as the crank or crank connection is between the rotary driving shaft and the take-up finger, it follows that the said finger is movable in a circular path, and although operated by rotary means it is nevertheless free of movement around the axis of said rotary driving 110 means, so that there is no tendency whatsoever of the thread being wound around the rotary driving means or being sucked into engagement therewith.

I claim as my invention:

1. In a sewing machine the combination of thread controlling means comprising nipper mechanism, take-up mechanism and a plurality of independent tubes through which the thread passes, one thread to each tube whereby the threads are maintained separated one from another.

2. In a sewing machine the combination of thread controlling means comprising nipper mechanism, take-up mechanism and one

- or more tubes having a slot extending lengthwise thereof and through which the thread passes.
3. In a sewing machine the combination of thread controlling means comprising nipper mechanism, take-up mechanism and one or more tubes having a slot extending lengthwise thereof and terminating in an enlarged eye portion and through which the thread passes.
4. In a sewing machine the combination of thread controlling means comprising nipper mechanism, take-up mechanism and one or more tubes through which the thread passes, said tubes being adjustable lengthwise thereof.
5. In a sewing machine, the combination of a thread take-up finger movable in a circular path, and rotary means connected with said finger for operating it without imparting thereto movement around the axis of said rotary means.
6. In a sewing machine, the combination of a rotary driving shaft, a thread take-up finger, and a crank between said shaft and said finger for imparting movement to the finger in a circular path from said shaft.
7. In a sewing machine, the combination of a thread take-up finger movable in a circular path, rotary means connected with said finger for operating it without imparting thereto movement around the axis of said rotary means, and means comprising an upwardly extending bent-over member or members for releasing the threads from said take-up finger.
8. In a sewing machine, the combination of a rotary driving shaft, a thread take-up finger, a crank between said shaft and said finger for imparting movement to the finger in a circular path from said shaft, and means comprising an upwardly extending member or members for releasing the thread from said take-up finger.
9. In a sewing machine, the combination of a thread take-up finger movable in a circular path, rotary means connected with said finger for operating it without imparting thereto movement around the axis of said rotary means, and means comprising an upwardly extending bent-over member or members for releasing the thread from said take-up finger, said finger and members being adjustable relatively to each other.
10. In a sewing machine, the combination of a rotary driving shaft, a thread take-up finger, a crank between said shaft and said finger for imparting movement to the finger in a circular path from said shaft, and means comprising an upwardly extending member or members for releasing the thread from said take-up finger, said finger and members being adjustable relatively to each other.
11. In a sewing machine the combination of a rotary main shaft, crank mechanism

connected therewith, a take-up finger connected with said crank mechanism for rotary movement, a plurality of upwardly extending bent over members effective to release the thread from said take-up finger and between which said finger rotates, and means for adjusting said members relative to said finger.

12. In a sewing machine, the combination of a thread take-up finger movable in a circular path, rotary means connected with said finger for operating it without imparting thereto movement around the axis of said rotary means, an adjustable member, a thread guide carried by said member, and thread detaching means also carried by said member for detaching the thread from said take-up finger.

13. In a sewing machine the combination of a rotary shaft, crank mechanism connected therewith, a take-up finger connected with said crank mechanism for rotary movement, an adjustable member, a thread guide carried by said member, and thread detaching means also carried by said member for detaching the thread from said take-up finger, said detaching means comprising a plurality of upwardly extending bent members located on opposite sides of the finger.

14. In a sewing machine the combination of a rotary shaft, crank mechanism connected therewith, a take-up finger connected with said crank mechanism, thread detaching means coöperating with said take-up finger and comprising a plurality of upwardly extending bent over members located at opposite sides of said take-up finger.

15. In a sewing machine the combination of a rotary shaft, crank mechanism connected therewith, a take-up finger connected with said crank mechanism, thread detaching means coöperating with said take-up finger and comprising a plurality of upwardly extending bent over members located at opposite sides of said take-up finger, and means for adjusting said members relative to said finger.

16. In a sewing machine the combination of a rotary shaft, crank mechanism connected therewith, a take-up finger connected with said crank mechanism, thread detaching means coöperating with said take-up finger and comprising a plurality of upwardly extending bent over members located at opposite sides of said take-up finger, means for adjusting said members relative to said finger, and means for adjusting said finger relative to said members.

17. In a sewing machine the combination of thread take-up means and thread nipper means, the latter comprising a pair of split resilient members, one coöperating with each of a pair of threads, whereby one thread passes under one member and over the other while the other thread passes over said first

member and under the other, and means for actuating said members.

18. In a sewing machine the combination of thread controlling means comprising 5 nipper means consisting of a pair of split resilient members, means coöperating therewith, a rotary take-up finger, means for rotating it, and thread detaching means coöperating with said finger and comprising a 10 plurality of upright bent members.

19. In a sewing machine the combination of thread controlling means comprising 15 nipper means consisting of a pair of split resilient members, means coöperating therewith, a rotary take-up finger, means for rotating it, thread detaching means coöperating with said finger and comprising a plurality of upright bent members, and thread 20 guiding means comprising one or more tubular guides through which the threads pass.

20. In a sewing machine the combination of thread controlling means comprising nipper means consisting of a pair of split, 25 resilient members, means coöperating therewith, a rotary take-up finger, means for rotating it, thread detaching means coöperating with said finger and comprising a plurality of upright bent members, and thread 30 guiding means comprising one or more tubular guides having a lengthwise extending slot and through which the threads pass.

21. In a sewing machine the combination of thread controlling means comprising nipper means consisting of a pair of split resilient members, means coöperating therewith, a rotary take-up finger, means for rotating it, thread detaching means coöperating with said finger and comprising a plurality of upright bent members, thread 40 guiding means comprising one or more tubular lengthwise adjustable guides having a lengthwise extending slot and through which the threads pass.

45 22. In a sewing machine the combination of thread nipper means, thread take-up means and thread guiding means, the latter comprising a plurality of tubes through which the threads separately pass.

50 23. In a sewing machine the combination of thread nipper means, thread take-up means and thread guiding means, the latter comprising one or more lengthwise adjustable tubes through which the thread passes.

55 24. In a sewing machine the combination of looper mechanism, nipper means, thread take-up means and thread guiding means comprising a plurality of lengthwise extending tubes for guiding the threads to the 60 looper mechanism, said tubes having staggered ends located adjacent to the looper mechanism.

25. In a sewing machine the combination of looper mechanism, nipper means, thread 65 take-up means and thread guiding means

comprising a plurality of lengthwise extending tubes for guiding the threads to the looper mechanism, said tubes having staggered ends located adjacent to the looper mechanism, and said tubes being adjustable 70 lengthwise thereof.

26. Thread controlling means for a sewing machine comprising a thread take-up finger operative to carry the threads only upward and backward to a point of cast-off and then casting off or dropping the threads, and means connected adjacent to the rear end of the finger for operating it, said finger being free of movement around the axis of said operating means. 75

27. Thread controlling means for a sewing machine comprising a rotary thread take-up finger operative to carry the thread only upward and backward, and means connected adjacent to the rear end of said finger 80 for actuating it, said finger being free of movement around the axis of said actuating means.

28. Thread controlling means for a sewing machine comprising a rotary thread 90 take-up finger operative to carry the thread only upward and backward, means connected adjacent to the rear end of said finger for actuating it, said finger being free of movement around the axis of said actuating 95 means, and a plurality of members between which said finger operates for detaching the thread from said finger.

29. In a sewing machine, the combination of a rotary shaft, crank mechanism connected therewith, a rock shaft operated from said rotary shaft, nipper mechanism connected with said rock shaft, a rotary take-up finger connected with said crank mechanism, means for guiding the thread to and 100 from the nipper mechanism and take-up mechanism and comprising tubes through 105 which the thread passes.

30. In a sewing machine, the combination of a rotary shaft, crank mechanism connected therewith, a rock shaft operated from said rotary shaft, nipper mechanism connected with said rock shaft, a rotary take-up finger connected with said crank mechanism, means for guiding the thread to and 110 from the nipper mechanism and take-up mechanism and comprising tubes through which the thread passes, certain of said tubes having an adjustment lengthwise 115 thereof.

31. In a sewing machine, the combination of a rotary shaft, crank mechanism connected therewith, a rock shaft operated from said rotary shaft, nipper mechanism connected with said rock shaft, a rotary take-up finger connected with said crank mechanism, means for guiding the thread to and 120 from the nipper mechanism and take-up mechanism and comprising tubes through 125 which the thread passes, certain of said tubes 130

having an adjustment lengthwise thereof, and means for detaching the thread from said take-up finger and comprising a plurality of upwardly extending bent over members located at opposite sides of the fingers.

32. In a sewing machine the combination of a rotary shaft, crank mechanism connected therewith, a rock shaft operated from said rotary shaft, nipper mechanism connected with said rock shaft, a rotary take-up finger connected with said crank mechanism, means for guiding the thread to and from the nipper mechanism and take-up mechanism and comprising tubes through which the threads pass, certain of said tubes having an adjustment lengthwise thereof, and means for detaching the thread from said take-up finger and comprising a plurality of said upwardly extending bent over members located at opposite sides of the fingers, said fingers being effective to carry the threads only upward and backward.

33. In a sewing machine, the combination of a rotary shaft having driving connections, and a rotary thread take-up finger directly connected adjacent to its rear end with one of said driving connections for rotary movement in a circular path, said finger being free of movement around the axis of said shaft.

34. In a sewing machine the combination of nipper mechanism, thread take-up means, and thread guiding means comprising a pair of tubes for conveying a pair of threads to the nipper mechanism and a pair of tubes for conveying the thread from the take-up mechanism, one thread in a tube of each pair whereby they are maintained separated.

35. In a sewing machine, the combination of nipper mechanism, thread take-up mechanism, looper mechanism, tubular guides for conveying the threads to the nipper mechanism, and tubular guides for conveying the threads from the take-up mechanism to the looper mechanism.

36. In a sewing machine the combination of nipper mechanism, thread take-up mechanism, looper mechanism, tubular guides for conveying the threads to the nipper mechanism, and tubular guides for conveying the threads from the take-up mechanism to the looper mechanism, said last guides being adjustable lengthwise thereof.

37. In a sewing machine the combination of nipper mechanism, thread take-up mechanism, looper mechanism, tubular guides for conveying the threads to the nipper mechanism, and tubular guides for conveying the threads from the take-up mechanism to the looper mechanism, said last guides being adjustable lengthwise thereof and having their ends in staggered relation relatively to the looper mechanism.

38. In a sewing machine the combination of a base, a driving shaft carried thereby

and having driving connections, a shiftable oil pan located under said connections and thread nipper mechanism partly carried by said oil pan.

39. In a sewing machine the combination of a base, a driving shaft carried thereby and having driving connections, a shiftable oil pan located under said connections and thread take-up means partly carried by said oil pan.

40. In a sewing machine the combination of a base, a driving shaft carried thereby and having driving connections, a shiftable oil pan located under said connections and thread handling means partly carried by said oil pan.

41. In a sewing machine the combination of a base, a driving shaft carried thereby and having driving connections, a shiftable oil pan located under said connections and thread nipper mechanism and thread take-up means partly carried by said oil pan.

42. In a sewing machine having a base, a driving shaft carried thereby, an oil pan located in said base and thread handling means partly carried by said oil pan.

43. In a sewing machine having a base, a driving shaft carried thereby, an oil pan located in said base and thread handling means partly carried by said oil pan and comprising thread nipper means and thread take-up means.

44. In a sewing machine having a base, a driving shaft carried thereby, a shiftable oil pan located in said base and thread handling means partly carried by said oil pan and comprising thread nipper means and thread take-up means, a part of each means carried by said oil pan having an adjustment relatively to said oil pan.

45. In a sewing machine, the combination of a rotary shaft, crank mechanism connected therewith, a take-up finger connected with said crank mechanism and projecting forwardly therefrom and having a thread engaging end located relatively remote to said crank mechanism, said finger having a rotary movement in a circular path imparted to its thread engaging end from the rear end thereof.

46. In a sewing machine, the combination of a rotary shaft, crank mechanism connected therewith, a take-up finger connected with said crank mechanism and projecting forwardly therefrom and having a thread engaging end located relatively remote to said crank mechanism, said finger having a rotary movement in a circular path imparted to its thread engaging end from the rear end thereof, and means for releasing the thread from said take-up finger, said finger and means being adjustable relatively to each other.

47. In a sewing machine, the combination of a rotary shaft, crank mechanism con-

nected therewith, a take-up finger connected with said crank mechanism and projecting forwardly therefrom and having a thread engaging end located relatively remote to 5 said crank mechanism, said finger having a rotary movement in a circular path imparted to its thread engaging end from the

rear end thereof, and means for releasing the thread from said take-up finger and adjustable relatively to said finger. 10

Signed at Nyack, county of Rockland, and State of New York, this 20th day of September, 1918.

JOHN P. WEIS.
